HERMETICALLY SEALED PACKAGE

Harry E. Townsend, Brooklyn, N. Y.; Title Guar-
antee and Trust Company executor of the
estate of said Harry E. Townsend, deceased

Application February 18, 1933, Serial No. 657,388

10 Claims. (Cl. 215—38)

My invention relates to packages, and has special reference to packages of the type in which a glass jar, tumbler or other receptacle is closed by a cap, usually of sheet metal, that is pressed 5 downwardly over the mouth of the receptacle into sealing position on an elastic gasket which is seated on a shoulder spaced a distance below the upper end of the receptacle, the cap being held sealed partly or entirely by atmospheric 10 pressure.

The object of my invention is to provide a novel and improved package of this character.

The several features of the invention will be clearly understood from the following description 15 and accompanying drawing, in which:

Figure 1 is a side elevation, partly in section, of a package embodying the features of my invention in their preferred form;

Fig. 2 is a detail sectional view, on an enlarged 20 scale, taken on the line 2—2 of Fig. 1, showing the closure of the package as it is about to compress the gasket;

Fig. 3 is a similar view showing the closure in 25 sealing position on the mouth of the receptacle;

Fig. 4 is a detail sectional view, on an enlarged scale, taken on the line 4—4 of Fig. 1, showing the manner in which the bowl of a spoon or other more or less wedge-shaped implement may 30 be used to remove the closure from the receptacle, the closure being shown partially lifted;

Fig. 5 is a view similar to Fig. 4 of a modified 35 form shown with the closure in sealed position;

Fig. 6 is a sectional view taken on the line 40 6—6 of Fig. 3.

My improved package as illustrated in the 45 drawing, is of the type of the one described and claimed in my pending application, Serial No. 638,741, filed October 20, 1932.

My improved package, as illustrated in the 50 drawing, comprises a glass jar 2, a closure or cap 4 which may be made of resilient sheet metal as customary, and an elastic gasket 6.

The jar is provided with a cylindrical mouth 55 portion 8, and is further provided, at the bottom of the cylindrical portion, with a narrow annular shoulder 10 arranged substantially horizontally to provide a seat for the gasket 6, and a downwardly and outwardly sloping surface 12 below the gasket seat.

The gasket 6, which is preferably substantially 60 square in cross section, is positioned over the cylindrical mouth portion 8 of the jar and on the seat 10. The gasket is made slightly smaller in diameter than the cylindrical mouth portion so

as to cause it to tend to hug the mouth portion when placed thereon.

The cap 4 is provided with a depending skirt having a cylindrical crown 14, an outwardly extending portion 16 and a downwardly extending 5 portion 18. The downwardly extending portion 18 is cylindrical and the outwardly extending portion 16 is preferably horizontal. The lower edge of the downwardly extending portion 18 is curled over to provide a stiffening bead 20.

When the cap is to be sealed on the jar in a vacuum sealing machine, it is first placed over the mouth of the jar and rests lightly on the top thereof, the gasket having been previously positioned on the mouth of the jar. Owing to the 15 rapidity with which the operator must place the caps on the jars, the caps are almost always placed in an unlevel condition, partly on the top of the jar and partly on the gasket. The jar, with the cap thus initially positioned thereon, is then 20 placed in the sealing chamber of the machine, the air exhausted from the jar, the cap pressed down to sealing position by mechanical means, air re-admitted to the sealing chamber to surround the jar, and the mechanical pressure on 25 the cap released. Atmospheric pressure together with other means to be described, then holds the cap sealed on the jar.

Glass jars as commercially used are not always 30 round, a considerable percentage having mouth portions that are slightly elliptical. Obviously, the crown of a cap used to seal such a jar must be large enough in diameter to fit over the major axis of the mouth of the jar. When, therefore, a cap so made is used on a jar the mouth portion 35 of which is round, the cap will usually not be accurately centered on the jar, and the gasket engaging portion of the cap will engage the gasket nearer its outer edge on one side of the jar than on the other, causing the cap to be sealed 40 unlevel on the jar. This not only tends to make the seal insecure, but results in an unsightly package, and makes the stacking of such packages for display purposes difficult and unsafe.

In the illustrated construction, in order to insure 45 that the cap shall be accurately centered on the jar when it is pushed down to sealing position, the jar is provided with projections 22 adapted to engage the cylindrical skirt 18 of the cap, and centre the cap on the top of the receptacle, even when the crown and skirt portions 50 of the cap are larger in diameter than the adjacent portions of the receptacle.

In the package herein described, the shape and 55 proportions of the gasket, the gasket seat on the

receptacle, the gasket compressing portion of the cap, and the manner of compressing the gasket are all preferably the same as in the package described and claimed in my said pending 5 application, Serial No. 638,741. The package of said pending application is also provided with projections for engaging and centering the cap during the sealing operation. In the package of the pending application, however, the projections 10 are on the cylindrical mouth portion of the jar, above the gasket seat, and are adapted to engage the cylindrical crown of the cap. In the present construction the projections are below the gasket seat and are adapted to engage the 15 cylindrical skirt 18 of the cap.

In the present construction, the cylindrical mouth portion 8 of the receptacle and the cylindrical crown portion 14 of the cap, are relatively short, and the downwardly extending portion 20 18 of the cap relatively long. A groove 24 is provided in the outer wall of the receptacle a slight distance below the gasket seat 10, the upper wall of the groove and the gasket seat forming the bottom and top walls or sides of an 25 annular ledge. The groove 24 forms a continuation of the sloping surface 12. Also, as in the prior construction, the lower edge of the skirt of the cap, when the cap is in sealing position on the jar, is somewhat spaced away from the sloping surface 12 to permit the insertion, between 30 the skirt and the sloping surface, of the point of a wedge shaped implement such as the bowl of a spoon 25. In the present construction, the inward movement of the implement is arrested by 35 the engagement of the end thereof with the ledge above the groove 24 so that there is no danger of violent displacement of the cap or gasket as they are removed.

Some products, such as hot preserves, can not 40 be sealed in a high vacuum. In this case the unbalanced atmospheric pressure available for holding the cap sealed on the receptacle may amount to very little. When the receptacle and cap are used for sealing such products, the frictional engagement of the projections 22 may aid materially in holding the cap in gasket compressing position on the jar until the contents cool sufficiently to create a substantial vacuum in the package. This is particularly true when the projections are formed as shown in Fig. 5, with their 45 lower portions tapering downwardly and inwardly. With this construction, when the cap is forced into sealing position, owing to the resiliency of the cylindrical skirt portion 18 reinforced by the bead 20, the lower edge of the skirt tends to lock beneath the adjacent portions of the projections, this being caused by the 50 tendency of the reinforced lower edge of the cap to return to its circular form after being distorted as it passes over the outer extremities of the projections.

As will be evident to those skilled in the art, my invention permits various modifications without departing from the spirit thereof or the scope 55 of the appended claims.

What I claim is:

1. In a package comprising a receptacle of the type having a mouth portion, an annular shoulder adjacent the lower end of said mouth portion, 70 an elastic gasket positioned on the annular shoulder, and a closure having a crown portion slightly larger than said mouth portion and having a resilient skirt adapted to compress the gasket on the annular shoulder, said closure being 75

applied by forcing it downwardly over the mouth of the receptacle, the improvement which comprises a plurality of projections formed on the receptacle below said annular shoulder, said skirt extending downwardly over and frictionally engaging said projections under tension. 5

2. The structure according to claim 1 in which the lower portions of the projections are inclined downwardly and inwardly.

3. The structure according to claim 1 in which the lower portions of the projections are inclined downwardly and inwardly and said skirt extends downwardly over and frictionally engages said projections with the lower edge of said skirt reinforced below the outer extremities of said projections so as to tend to cause the closure to lock beneath said extremities. 15

4. The combination of a receptacle having a cylindrical mouth portion, an annular gasket seating ledge adjacent the lower end of said cylindrical mouth portion and a downwardly and outwardly inclined annular face below said ledge, an elastic gasket positioned on said ledge, and a closure having a flat top portion and a depending skirt portion adapted to compress said gasket 20 on said ledge, said closure being applied by forcing it downwardly over the mouth of the receptacle, the lower edge of the skirt of the closure being a substantial distance below the top of said inclined face of the receptacle and being 25 spaced a substantial distance outwardly therefrom, whereby the closure may be removed by the insertion of a wedging or prying tool between said lower edge of the skirt and said inclined face, the under side of said annular ledge being adapted 30 to limit the inward and upward movement of the wedging or prying tool to prevent violent displacement of the closure or gasket.

5. In a package of the type comprising a receptacle having an annular shoulder formed in 40 its outer wall a distance below its upper end, an elastic gasket positioned on the annular shoulder, and a closure made of resilient sheet material having a depending skirt provided with a portion adapted to compress the gasket on the shoulder 45 of the receptacle and having an annular portion below the gasket compressing portion, the said skirt above and below the gasket compressing portion being spaced from the outer wall of the receptacle, the improvement which comprises a 50 plurality of spaced projections formed on the outer wall of the receptacle, below the annular shoulder, for engaging said annular portion, whereby when the closure is pushed down to sealing position on the receptacle it is properly centered on the receptacle by said projections. 55

6. The combination of a receptacle having an open end, a closure having a flat top portion and a depending skirt portion adapted to be placed over the open end of the receptacle, and a gasket 60 adapted to be compressed between opposed faces of the receptacle and closure, the receptacle being provided with a downwardly and outwardly inclined face positioned a distance below its upper end and the lower edge of the skirt of the closure 65 when the closure is sealed on the receptacle being a substantial distance below the top of the inclined face and being spaced a substantial distance outwardly from the said face, whereby the 70 closure may be removed from the receptacle by inserting a wedging or prying implement between the said inclined face and the said lower edge of the skirt of the closure, the receptacle being provided with an annular portion projecting out- 75

wardly above the top of the said inclined face to limit the inward and upward movement of the said wedging or prying implement.

7. A package comprising a receptacle having an open end, a closure having a depending skirt positioned over said open end, and a gasket, the wall of said receptacle and said skirt having portions engaging opposed sides of the gasket, the outer wall of the receptacle below said gasket-engaging portion being provided with circumferentially spaced projections for engaging the skirt of the closure when the closure is pressed downwardly over said open end, said projections causing the closure to be accurately centered on the receptacle.

8. A package comprising a receptacle having an open end, a closure having a depending skirt positioned over said open end, and a gasket, said receptacle and said closure having opposed faces engaging opposite sides of the gasket, and the outer wall of the receptacle below said gasket-engaging portion being provided with circumferentially spaced projections for engaging the skirt of the closure when the closure is pressed downwardly over said open end, said projections causing the closure to be accurately centered on the receptacle.

9. A package comprising a receptacle having

an open end, a closure having a depending skirt positioned over said open end, and a gasket, the said receptacle and said skirt having portions engaging opposed sides of the gasket, the skirt of the closure extending a distance below the gasket-engaging portion and being spaced slightly from the wall of the receptacle, the improvement which comprises the wall of the receptacle being provided with projections for frictionally engaging the skirt of the closure below the level of the gasket, said closure being applied by forcing it downwardly over the mouth of the receptacle.

10. In a package of the class described, a receptacle having a downwardly and outwardly sloping surface spaced a distance below its upper end, a closure for the receptacle having a depending skirt spaced outwardly from said sloping surface and extending a distance below the top thereof, said receptacle and closure having opposed gasket-engaging faces, and an elastic gasket positioned between said faces, the space between said sloping surface and said skirt being unobstructed whereby a wedging implement may be freely inserted between said sloping surface and said lower edge of the closure to displace the closure by wedging action.

HARRY E. TOWNSEND.
